UNITED STATES PATENT OFFICE.

PIERRE J. PAQUET, OF SALEM, WEST VIRGINIA.

GLASS-BLOWING APPARATUS.

1,140,314.

Specification of Letters Patent.

Patented May 18, 1915.

Application filed January 5, 1914, Serial No. 810,487. Renewed April 16, 1915. Serial No. 21,847.

To all whom it may concern:

Be it known that I, PIERRE J. PAQUET, a citizen of the United States of America, residing at Salem, in the county of Harrison 5 and State of West Virginia, have invented certain new and useful Improvements in Glass-Blowing Apparatus, of which the following is a specification.

This invention relates to certain new and 10 useful improvements in glass blowing apparatus and more especially to such class of devices in which a blowing and a suction is mechanically effected.

An object of the invention is to provide an 15 air blowing and an air suction member operatively connected with the blow pipe for operating upon the glass cylinder which is being manufactured, for instance in the process of making sheet glass.

20 A further object is the provision of an elevating device for the blow pipe with its glass cylinder so arranged that the blow pipe is automatically disengaged from the air tube at a predetermined point in its vertical line of travel.

Another object is to provide in connection 25 with an air tube having an operating suction and blowing fan, a graduating valve for the tube adapted for automatically opening and closing upon imparting vertical movement to the blow pipe and said tube.

A further object is to provide an air 30 damper in the air tube of the blowing system governable for exhausting desired quantities of air therefrom.

A still further object is the connection of 35 a separate suction and blowing fan with the pipes of the air tube system and whereby said fans may be governed at will in connection with the air tube and the blow pipe while the piping of the system is advantageously arranged for allowing a vertical movement of the blow pipe relative to the main stationary piping.

40 Another object is the provision of a vertically movable hoist having stationary vertical guides and furnished with means for disengageably supporting the blow pipe and air tube, each in relatively movable positions.

50 A still further object is to provide a 45 swinging horse adapted for receiving the glass cylinder when vertically positioned upon the hoist and operable for moving the cylinder to a horizontal position suitably cushioned by means carried by the horse.

With these objects in view and others that will appear as the nature of the invention is better understood, the same consists in the novel combination and arrangement of parts hereinafter fully described, illustrated 60 in the accompanying drawings and pointed out in the appended claims.

In the drawings forming a part of this application and in which like reference numerals designate corresponding parts 65 throughout the several views:—Figure 1 is a side elevation of the apparatus illustrating the bait of the blowing pipe as collecting its quantity of glass from within the collecting ring of the glass pot, the ring and 70 pot being shown in section. Fig. 2 is a sectional detail view of the regulating valve in the air pipe of the system. Fig. 3 is a view similar to Fig. 1 but illustrating the glass cylinder as completed and with the blow 75 pipe separated from the air tube, the air tube, blow pipe and cylinder being shown in their elevated positions. Fig. 4 is a sectional detail view of the air damper found in the air tube. Fig. 5 is an enlarged detail view of 80 the tripping hoist mechanism supporting the air tube and blow pipe, the air system pipe and glass cylinder being broken away. Fig. 6 is a detail view of the regulating valve shown in Fig. 2 looking into the piping and 85 one of the connections being shown in dotted lines. Fig. 7 is a side elevation of the swinging horse about to engage the vertically suspended glass cylinder, and Fig. 8 is a similar view showing the cylinder resting horizontally upon the horse. 90

In the operation of mechanically blowing glass into cylinders for the manufacture of sheet glass it is desirable to provide a carrier for the blow pipe and bait, whereby the 95 latter may receive the desired quantity of glass from a point within the collecting ring and may then be elevated during the blowing operation and until the completion thereof while a suction device is serviceable 100 for then exhausting the air from the cylinder. It is now devised therefore to provide a blow pipe 10 having an upper and a lower annular ring 11 and 12 respectively, while the pipe at the bottom thereof terminates in 105 the usual bait 13. The air tube 14 is adapted to fit over the upper end of the blow pipe 10 and rest upon the upper side of the ring 11, while this tube is connected by the regulating valve 15 illustrated in Figs. 2 and 6 110

to the hinged piping 16 and 17 of the stationary air piping 18 of the system.

For supplying air under pressure to the piping system for use by the blow pipe 10, 5 a blower or fan 19 is preferably utilized communicating with the piping 18 by the connecting pipes 20, it being also possible however if desired to connect an air pressure reservoir direct to the piping, the air 10 being furnished to the reservoir by an air compressor.

A suction fan 21 communicates with the connection 20 by means of the piping 22 and the transverse pipe 23, while the upwardly 15 turned end 24 of the pipe 22 is open to the atmosphere and adapted to be closed as desired by the damper 25 fitting thereover and having the operating rod 26. A damper 27 within the connecting pipe 20 governs the 20 flow of air from the fan 19 to the system, while a similar valve 28 in the transverse pipe 23 controls the suction action of the fan 21 upon the air piping system.

A hoist block 29 is provided upon one or 25 both of its opposite sides with rings or eyes 30 slidably engaging the guide rods 31 secured to the ceiling and passing therethrough. A hoisting cable 32 passes over the pulley 33 also secured to the ceiling and 30 is connected to the upper end of the hoist block as at 34, it being noted that the weight of the block normally retains the same in its lowered position, while the cable is utilized as an elevating means.

35 Three hooks or open semicircular brackets 35 are secured in alinement to the inner face of the block 29 and adapted to receive the blow pipe therein with the ring 11 supported by resting upon the upper face of 40 the hook 35. With the air tube 14 resting upon the ring 11, a further hook 36 upon the block 29 and similar to said hooks 35 is adapted to receive and assist in positioning 45 said air tube while a pivoted hook 37 of similar form and provided with a rear extension or handle 38 is pivoted to the top of said block as at 39, while said hook is normally positioned and swung beneath the annular ring 40 of the tube 14 as illustrated 50 in Fig. 1.

With the apparatus positioned as shown in Fig. 1, the bait has received a quantity of glass 41 from a point within the annular collecting ring 42 positioned upon the molten glass 43 of the pot 44. With the hooks 35 positioning the blow pipe 10 and the pipe ring 11 resting upon the upper hook, an upward movement of the hoist block being imparted by the cable 32 elevates not only the blow pipe 10 and its bulk of glass 41, but also the air tube 14 resting upon said ring 11, so that the valve 27 may be opened to allow the fan 19 to blow air directly through the piping system to the blow pipe 65 and its glass, during the drawing operation

and thereby forming the glass into a cylinder 45 simultaneously with its upward movement.

When desired to exhaust the air from the glass cylinder 45, the blower valve 27 may 70 be closed and the suction valve 28 opened, whereby, with the damper 25 opened, the suction fan 21 will accelerate and thereupon a closing of the damper 25 will forcibly exhaust the air from the piping system and 75 the glass cylinder 45.

The graduating valve 15 consists of the connecting pipe sections 46 and 47, each having a portion of its diameter closed by a block 48 and so arranged that the communicating passage is substantially half open when the pipe hinge and the piping are positioned lowermost as shown in Fig. 1, but will be opened at its widest extent when the pipe hinge is positioned at its upper 85 limit of travel as shown in Figs. 3 and 6. The molten glass being gathered as shown in Fig. 1 with the blow pipe and bait in its lowermost position, the hoisting mechanism is elevated as rapidly as desired, while the 90 blowing and suction fans 19 and 21 are suitably regulated for their desired effect upon the glass. At substantially the limit of the upward travel of the hoist block, the regulating valve 15 will be automatically fully 95 opened by means of the pipe hinge blocks as hereinbefore described, while the arm 38 of the hook 37 will engage the stationary hook 49 secured to some stationary member 50, so that the continued upward movement 100 of the hoist block tilts the hook 37 upwardly upon its pivot 39 whereby said hook engages beneath the collar 40 of the tube 14, automatically unseating said tube from the supporting ring 11 and entirely disengaging 105 said tube from the blow pipe as best shown in Fig. 5.

Within the air tube 14 a plate or cylindrical sleeve 51 is positioned adapted to closely fit therein and provided with a projecting pin 52 protruding through the angular slot 53 of the tube and whereby the sleeve may be given a partial rotation as well as a limited vertical movement. Relatively large and small air ports 54 and 55 are provided 115 through said sleeve which are adapted to register with the vertical portion of said slot 53 upon the proper manipulation of the pin 52 as will be at once evident from an inspection of Fig. 5 of the drawings. 120

The complete operation of the device will be apparent from the above detail description from the time of attaching the bulk of glass to the blow pipe bait until the blow pipe with its completed cylinder is automatically disconnected from the air tube. The action of the blowing as well as the suction fan for operating upon the glass through the air piping is also clear and the manual regulation of both blowing and suction air as 125 130

well as the automatic regulating valve 15. Whenever desired also, the sleeve valve 53 of the air tube 14 is regulated by the pin 52 allowing a desired quantity of air to escape 5 from the exits 54 and 55.

Take down device.—Upon a completion of the glass cylinder 15 it is designed to remove the same from the hoist by means of the horse consisting of the frame 60 hinged 10 at 61 to the floor 62. A longitudinal slot 63 at the upper end of the frame is engaged by the sliding roller 64 rigidly secured to the endless belt 65, which belt passes over the drum 66 and the pulley 67, thus giving 15 a swinging movement to the frame upon a movement of the belt by means of the motor 68 in either direction and controlled as desired. At the upper end of the frame 60 an extending arm 69 braced by the rod 70 terminates in a hook 71 of semicircular form and adapted to engage beneath the ring 12 of the blow pipe 10 and to thereby support the same and upon a downward movement of the frame to elevate the blow pipe off the 25 hook 35 of the block 29 upon which it has been resting. Spring mounted semicircular brackets 72 are spaced apart from the frame 60 and adapted to receive the glass cylinder cushioned thereon, while the frame 60 is 30 provided with a spring-pressed foot 73 upon its lower side and adapted to rest upon the floor when the frame and cylinder are positioned horizontally as shown in Fig. 8.

The operation of the take down device 35 will be clear from this description, it being designed to remove the completed glass cylinder from its support and to change its position from the vertical to the horizontal reclining position without any liability of 40 injury to the cylinder. It is apparent that the cylinder may then be transferred from the horse or may be treated thereon or annealed in the usual manner.

While the forms of the invention herein 45 shown and described are what are believed to be preferable embodiments thereof, it is nevertheless to be understood that minor changes may be made in the form, proportion and details of construction without deviating from the spirit and scope of the invention as set forth in the appended claims.

I claim:

1. A glass apparatus comprising in combination with a blow pipe and bait, an air tube communicating with said pipe, suction and blowing air pipes communicating 55

with said tube, means for vertically moving said blow pipe, a regulating valve automatically openable upon the extreme upward movement of said air tube, and means carried by said vertical moving means and engaging said air tube adapted for automatically disconnecting the same from the blow pipe.

2. A glass apparatus comprising a blow 65 pipe and bait, an air tube adapted to fit over said blow pipe, a vertically movable hoist block, supporting means carried by said block and engaging said blow pipe, a pivoted means carried by said block and 70 adapted for automatically imparting separating relative movement between said tube and pipe at the uppermost point of movement of the block.

3. A glass apparatus comprising a blow 75 pipe, a bait at the lower end of said pipe, and an annular ring adjacent its upper end, a vertically movable hoist block, a hook secured to said block supportingly engaging said ring, an air tube mounted over said pipe 80 and upon said ring, an annular ring upon said tube, a pivoted hook upon said hoist block in engagement with said tube ring and adapted for automatically imparting separating movements between said tube and 85 pipe at the extreme upper position of said block.

4. A glass apparatus comprising a blow pipe, a bait at the lower end of said pipe and an annular ring adjacent its upper end, 90 a vertically movable hoist block, a hook secured to said block supportingly engaging said ring, an air tube mounted over said pipe and upon said ring, an annular ring upon said tube, suction and blowing air 95 pipes communicating with said tube, a regulating valve automatically openable upon the extreme upward movement of said air tube, a pivoted hook upon said hoist block, a stationary member in the line of movement 100 of said hook and adapted for contacting thereby at the extreme upper position of said block, said hook upon such contact being adapted for automatically imparting relative movement between said tube and 105 pipe.

In testimony whereof I affix my signature in presence of two witnesses.

PIERRE J. PAQUET.
